UNITED STATES PATENT OFFICE.

HARRISON H. EATON, OF BEVERLY, MASSACHUSETTS, ASSIGNOR TO UNITED SHOE MACHINERY COMPANY, OF PATERSON, NEW JERSEY, A CORPORATION OF NEW JERSEY.

WORK-BENCH.

1,151,576.

Specification of Letters Patent. Patented Aug. 31, 1915.

Application filed August 31, 1914. Serial No. 859,423.

To all whom it may concern:

Be it known that I, HARRISON H. EATON, a citizen of the United States, residing at Beverly, in the county of Essex and State 5 of Massachusetts, have invented certain Improvements in Work-Benches, of which the following description, in connection with the accompanying drawings, is a specification, like reference characters on the drawings 10 indicating like parts in the several figures.

This invention relates to shoemakers' work benches and more particularly to such work benches which are especially adapted for use in connection with tack driving shoe machines examples of which are the pulling-over and tacking machines of the type shown in United States Letters Patent No. 1,029,387, dated June 11, 1912, and the lasting and tacking machines of the type shown 15 in United States Letters Patent No. 1,081,872, dated Dec. 16, 1913.

It is the shoe factory custom for machine operators to make use of these benches to hold several shoes at a time both before and 20 after the shoes have been subjected to the operation of the machine and also to hold the shoe for such manual manipulations as may be required in connection with the pulling-over and the lasting operations. It is 25 also a shoe factory custom, for which there are various satisfactory reasons, to run the pulling-over machines and the lasting machines so often, at times when no shoe is in 30 position to receive the tacks, as to scatter a good many tacks upon the work bench of the machine. A substantial amount of injury 35 is done to the uppers of shoes by scratches received from the tacks that gather upon the work benches heretofore employed in 40 connection with pulling-over machines and lasting machines, notwithstanding that good operators make a practice of frequently brushing the tacks off their benches on to the floor. Another condition is that these unused tacks, expelled by the machine when no 45 shoe is in position to be fastened by them, are wasted for when they are once dropped on the floor their value is too small to warrant the time required to gather them and 50 clean them from the dirt with which they become mixed. While some attempts have been made to lessen these evils, the alleged advantages of the proposed constructions have not predominated over their disadvan-

tages to such an extent that the proposed devices have to any extent superseded the old-fashioned wooden bench upon which shoes have continued to be scratched and tacks wasted.

The object of this invention is to meet the 60 described conditions with a shoemaker's work bench which will eliminate the evils complained of while providing a bench which will have all of the characteristics of convenience and strength desired by shoemakers and the low cost of construction which will make its adoption desirable as a part of the factory equipment.

With this object in mind this invention provides a frame constructed and arranged 70 to provide a suitable support for a grille cover through which tacks will assuredly fall instead of lodging thereon when they are expelled from the machine. The frame also provides a raised flange extending 75 around the ends and rear side of the bench to serve as a retaining wall for the shoes, the flange being omitted from the front edge of the table which is substantially flush with its grille top. The frame also presents 80 downwardly inclined rear and end walls extending from substantially the vertical planes of the ends and rear side of the table to a depending tubular collar. This collar is adapted to receive and is provided with 85 means for interlocking with a receptacle which makes a close fit therewith, the whole being arranged to assuredly catch the loose tacks which are expelled from the machine, 90 guide them unfailingly to the receptacle where they are collected and safely retained so that neither the bench top nor the floor is littered with tacks and no tacks lodge where they can scratch a shoe. The frame is advantageously provided with an integral at- 95 taching bracket by which the table can be securely fastened to the machine post by the use of only two lag-screws.

The whole is extremely simple and economical of construction because it, as de- 100 scribed, consists of only three parts each of which can be cast, or alternatively the bench top can be stamped out of heavy sheet metal, and can be prepared for use with little or no machine work. The frame is preferably 105 provided with a bearing to receive a last spindle, the depending stem of which extends through the frame to the floor where

it is provided with a suitably broadened foot. The frame is confined between the usual base flange, the last spindle and a nut on the stem so that the last spindle upon which more or less straining and pounding of the shoe takes place, instead of being an element of weakness to the work bench, constitutes an effective strengthening element which rigidly supports and braces the work bench at one of its outer corners.

The work bench will now be described in connection with the accompanying drawings and then the characteristic features of it upon which protection is sought will be pointed out in the claims.

Figure 1 of the drawings is a side elevation of a lasting machine equipped with a work bench embodying this invention in the best form now known to me, and Fig. 2 is a perspective view of the work bench attached to the post of the machine.

The illustrated machine has a post 2 and a head in which is operated a tack driver 3 and other usual associated parts of a lasting and tacking machine.

The work bench comprises a frame 1 having substantially vertical end and side walls which are formed with a flange or ledge 4 on their inner sides to afford support for the bench top 5 which is a grille or open-work plate which may be either cast or stamped out of stiff sheet metal to present narrow longitudinal and transverse connecting members and relatively wide openings between them as shown in Fig. 2. The connecting members may be convex enough on their upper faces to insure that tacks will not lodge on them. The plate may be formed in two pieces, as shown, and it may be cast instead of cut from sheet metal. The frame is formed with relation to the bench top supporting ledge 4 with an upstanding flange 6 on the rear of the bench and on each of its ends to present a work-retaining wall, the wall on the ends tapering down to the front edge which is preferably flush with the bench top.

There is formed integral with the frame an attaching bracket presenting to the machine post 2 a three point bearing at 8, 9, 10, the bearing points 8 and 9 being located above the bench top and the point 10 below it as shown in Fig. 1. The bracket is provided with holes for two lag bolts 11 located above the bench top and threaded into the post 2. The described arrangement provides a rigid and strong attachment of the work bench to the machine post and permits the work bench to be easily attached to machines which are already out in use in shoe factories. The frame 1 also presents end walls which are inclined downwardly and inwardly and a rear wall which is inclined downwardly and forwardly and merge into a collar 12 from which project radially two

studs 13. The collar receives the third part of the apparatus which is a tack receptacle 15 into which all tacks which fall upon the bench and through the top plate 5 are guided by the inclined side walls of the frame.

The receptacle 15 is formed with upright slots in its inner face having lateral offsets at 14 to receive the studs 13 and constitute therewith a bayonet joint type of lock for attaching the receptacle 15 in position to collect the tacks. The tacks are thus promptly gathered, kept clean and saved while heretofore they have been first a source of damage to the shoes on the work bench and then have become mixed with dirt and trash and wasted. This economy is effected without the use of any operating mechanism and by a collector which is incorporated in a usual and necessary adjunct to the machine, namely, the work bench.

Furthermore, this invention replaces the old wooden work bench previously used with one which, because of its simplicity of design and construction and its durability, can be provided and used without substantially greater expense than the old objectionable types of work benches.

Finally, and most important of all the advantages of this invention, the described work bench saves to the shoe manufacturer in a short time its entire cost by eliminating scratches and other damage to the finished surface of the shoe uppers.

Advantageously the common "spindle" for holding a last during manual operations on the shoe, such as pincering and pulling the upper and pounding down the heel seat after lasting, is combined with the work bench in a way to strengthen the latter. To this end the frame 1 is formed in one front corner with a hole or bearing for the stem 18 of the last spindle 20 the base 22 of which is clamped down upon the wall of said bearing by a nut 23. The stem 18 is preferably extended to the floor and provided with a suitably broadened foot, thereby affording additional rigid support for an end portion of the bench most remote from the points of attachment of the bench to the machine post 2.

Having explained the nature of this invention and how it is to be used, and pointed out some of the advantages secured by the described construction, I claim as new and desire to secure by Letters Patent of the United States:

1. A shoemaker's work bench adapted for attachment to the post of a lasting and tacking machine and comprising a frame having an attaching bracket presenting a three-point bearing to the machine post, means for securing the bracket to the post, a top plate supported by the frame and formed to afford a support for shoes while causing tacks falling thereon to pass through the plate, a tack

collecting receptacle and means for securing the receptacle to the frame and for guiding the tacks to the receptacle.

2. A shoemaker's work bench adapted for attachment to the post of a lasting and tacking machine and comprising a frame, an attaching means for connecting the frame to the post, said frame presenting means for supporting a top plate and having a retaining wall projecting above the top plate on the rear side and the ends of the bench, and a top plate constructed to hold shoes while causing tacks falling thereon from the machine to pass through the plate.

15 3. A shoemaker's work bench adapted for attachment to the post of a lasting and tacking machine and comprising a frame, on its inner faces a top-plate supporting ledge and above said ledge a work-retaining wall on 20 the rear side and the ends of the frame extending from near the front of the bench along one end and across the rear side along the other end to near the front side of the bench, and a top plate removably sustained 25 on said ledge and constructed to hold shoes and to cause tacks falling thereon to pass through it.

4. A shoemaker's work bench adapted for attachment to the post of a lasting and tacking machine and comprising a frame having an open top, a top-plate supporting ledge and walls inclined toward an outlet, an open-work top plate supported on said frame and constructed to support shoes and 35 to cause tacks falling on the bench to pass through into the frame, and a receptacle detachably secured to the frame to collect the tacks passing through the outlet.

5. A shoemaker's work bench adapted for 40 attachment to the post of a lasting and tacking machine and comprising a frame having an attaching bracket presenting a three-point bearing to the machine post, means for securing the bracket to the post, a last spindle having a base and having a stem extending 45 through the frame and adapted to rest on the floor, a nut threaded on the stem below the frame and between which and the spindle base the frame is clamped to afford 50 auxiliary support for the frame, and a bench top plate supported by the frame and comprising a rigid metal plate provided with a plurality of series of openings for the pas-

sage of tacks and having integral portions separating adjacent openings.

6. A shoemaker's work bench adapted for attachment to the post of a lasting and tacking machine and comprising a frame having an attaching bracket, means for connecting the bracket to the machine post, an open-work top plate constructed to afford support for shoes while causing tacks falling thereon to pass through the plate, and a tack receptacle removably attached to the frame and to which the frame conducts tacks which 65 pass through the top plate.

7. A shoemaker's work bench adapted for attachment to the post of a lasting and tacking machine and comprising a frame having an attaching bracket presenting a three-point bearing to the machine post, two of the bearing points being located above the shoe supporting top face of the bench and one bearing point therebelow and two bolts 70 extending through holes in the bracket below said upper bearing points and above the said top face and threaded into the machine post, substantially as described.

8. A work bench for a shoe stretching and nailing machine comprising a grille, a frame 80 for supporting said grille and having an inclined bottom terminating in a tack discharging neck, and a tack receiving receptacle detachably secured to said frame.

9. A work bench for a shoe stretching and nailing machine comprising a grille, a frame 85 for supporting said grille, the portion of the frame below said grille being funnel-shaped and terminating in a tack discharging neck, and a tack-receiving receptacle detachably 90 secured to said neck.

10. A work bench for a shoe stretching and nailing machine comprising a removable grille, a frame provided with a shoulder for supporting said grille, the portion of the 95 frame below said grille being funnel-shaped and terminating in a tack discharging opening, and a tack-receiving receptacle detachably secured in alignment with said opening.

In testimony whereof I have signed my 100 name to this specification in the presence of two subscribing witnesses.
